UNITED STATES PATENT OFFICE.

KARL VÖLLER, OF DUSSELDORF, GERMANY, ASSIGNOR TO RHEINISCHE METALL-WAAREN- UND MASCHINENFABRIK, OF DUSSELDORF-DERENDRÖF, GERMANY, A CORPORATION OF GERMANY.

MEANS FOR REMOVING AMMUNITION-SHELLS.

1,088,490.

Specification of Letters Patent.

Patented Feb. 24, 1914.

Application filed June 12, 1911. Serial No. 632,626.

To all whom it may concern:

Be it known that I, KARL VÖLLER, engineer, a subject of the German Emperor, residing at 12 Scharnhorststrasse, Dusseldorf, 5 Germany, have invented new and useful Improvements in Means for Removing Ammunition-Shells, of which the following is a specification.

It is often necessary to remove the cartridge cases from the projectile for the purpose of altering the amount of the charge in cartridges used in guns for high angled fire. Up to the present the cartridges for high angled fire have been constructed with 10 a weaker connection between the projectile and the case, so that the two parts could be separated by hand, but in all such constructions the danger exists of some damage occurring especially during the transport of 15 the ammunition. For this reason it is preferable that the connection between the cartridge case and the projectile should be as strong for high angled fire guns as for ordinary field guns.

20 According to the present invention a device can be applied to the gun cradle by which the case can be detached and removed from the projectile however firmly they may be attached.

25 The accompanying drawings show a construction for carrying out the invention, in which—

Figure 1 is an elevation of the device attached to the cradle of the gun, Fig. 2 is a 30 section through the line 2—2 of Fig. 1, Fig. 3 is a view looking from the rear. Fig. 4 is a plan view corresponding to Fig. 1, and Fig. 5 is a section through the line 5—5 of Fig. 4.

35 Attached to the gun cradle is a support *a*, for the projectile. A support *b* for the cartridge case is arranged to slide in suitable guides in the support *a*. The cartridge is placed so that the projectile rests in the support *a* and the case in the support *b*.

40 The projectile is held firmly in the support *a* by a cover *a'* which can be turned about a hinge *d* in the support. A lever *e* holds this cover down by means of two hooks 45 *i* connected to the eccentric bolt *f*. The projectile is prevented from any axial displacement in the support *a*, by its copper band *g* and central ring *h*, when the cover *a'* is closed.

When the lever *e* is moved in the direction 55 shown by the arrow, the hooks *i* are raised by a projection *k* which moves in a groove, and are moved sufficiently far around to allow the cover *a'* to be opened to insert or remove a projectile. The cartridge case lies 60 by a projection *k* which moves in a groove, thereof so that it cannot be displaced in its support. The case is withdrawn by the movement of the support *b* by means of the lever *c*, which is rigidly connected with the 65 spindle *m* which latter has its bearings in the support *a*. To the other side of this spindle is fixed a smaller lever *n*. The larger lever *c* and the smaller lever *n* are connected by a bolt *o* to the two sides of the support *b*. 70 If the lever *c* is turned, the small lever by means of its attachment to the spindle *m* is also turned through the same angle, and the support *b* is displaced in its support *a* (Fig. 5) and the case drawn off or pressed on. 75

The device need not be attached to the gun cradle: It may for example be fastened to the limber or to the ammunition wagon or elsewhere.

I claim as my invention:

1. A device designed to be secured to a gun for removing cartridge cases from projectiles, comprising a fixed support for the projectile, a clamp mounted on said support for locking the projectile thereto, a 80 second support for the cartridge case, and manually-operable means mounted on the first mentioned support and engaging the second support for effecting a relative movement between the two supports. 85

2. A device designed to be secured to a gun for removing cartridge cases from projectiles, comprising a fixed support for the projectile, a clamp mounted on said support for locking the projectile thereto, said support having an extension, a second support 90 slidably mounted on said extension and designed to receive and hold the cartridge case, and manually-operable means mounted on said first mentioned support and engaging 95 said second support for effecting a relative movement between the two supports.

3. A device designed to be secured to a gun for removing cartridge cases from projectiles, comprising a fixed support for the 100 projectile, a clamp mounted on said support for locking the projectile thereto, manually operable means on said support for locking

the clamp to said support, a second support 5
slidably mounted on the first mentioned support
and having a groove to receive the flange of the cartridge case, and a manually-
operable lever mounted on the first mentioned support and connected to the second support for effecting a relative movement
between the two supports.

4. A device designed to be secured to a
10 gun for removing cartridge cases from projectiles, comprising a fixed support for the projectile, a clamp pivoted to said support
for locking the projectile thereto, said support having an extension, a support for the

cartridge case slidably mounted on the first 15
mentioned support and having a groove to accommodate the flange of said case, and a lever fulcrumed on the first mentioned support and connected to said cartridge case support for moving it relatively to the first 20
mentioned support.

In testimony whereof I have signed my name to this specification in the presence of two subscribing witnesses.

KARL VÖLLER. [L. s.]
